Attorney.

UNITED STATES PATENT OFFICE.

JAMES B. MILLER, OF ST. LOUIS, MISSOURI.

FURNACE.

Application filed August 19, 1925. Serial No. 51,196.

This invention relates to furnaces for heating articles and more particularly to such furnaces as may be used for heating articles in preparation for forging operations.

One of the objects of this invention is to provide a furnace in which a number of articles may be delivered as required ready for the forging or similar operation.

Another object is to provide such a furnace 10 to which the articles may be fed in succession and from which they may be delivered when thoroughly heated.

Another object is to provide a furnace to which articles may be delivered successively 15 from a stack of articles to be heated and delivered as required for subsequent operations.

Further objects will appear from the following description taken in connection with the accompanying drawing in which:

20 Figure 1 is a side elevation of a furnace embodying this invention;

Figure 2 is an end view taken from the right hand end of Figure 1;

Figure 3 is an end view from the left hand 25 end of Figure 1;

Figure 4 is a longitudinal section of part of the delivery chute;

Figure 5 is a transverse section of the 30 hearth taken about on line 5—5 of Figure 1; and

Figure 6 is a detail plan view of the feeding mechanism.

Referring to the accompanying drawings 1 designates a support or frame which may 35 be constructed of angle iron suitably framed together and on which is mounted a hearth 2. The hearth 2 may be constructed of cast iron or other suitable material in the form of a long hollow casting having a flue 3 extending lengthwise therethrough. The hearth 2 is provided with an upper inclined surface 4 upon which the articles to be heated may rest and along which they may be moved during the heating operation. At the lower edge of 45 the inclined surface 4 there is formed a right angled face 5 adapted to provide a guide for the articles moving over the hearth.

At the rear or right hand end, Figure 1, of 50 the hearth 2 an opening in the lower face provides an inlet to the flue 3 to which the spout 6 of a blower 7 may be attached. The blower 7 may be driven by a suitable motor 8 and delivers air through the spout 6 to the flue 3. The air passing through this flue serves to 55 cool the hearth so as to keep the same from overheating. At the forward end of the

hearth the flue 3 has an outlet 9 to which may be attached an air duct 10 in the form of a pipe or tube which passes to the air inlet of a suitable burner 11. The burner 11 may be 60 of any suitable type. In the illustration it is represented as an oil burner having suitable connections 12 with a source of oil supply. It will be noted that the air delivered to the burner is first passed through the flue 3 65 whereby the hearth is cooled and the air is heated preparatory to delivering the same to the burner 11. A suitable furnace chamber or muffle 13 is built over the hearth 2 and is provided with an inlet 14 through which the 70 flame of the burner 11 may be projected into the furnace chamber and directed on the hearth 2.

Over the rear end of the hearth 2 an inclined chute 15 is mounted in which the articles to be heated may be stacked. The articles are preferably stacked, one upon the other, in the chute with the lower-most article resting on the upper surface 4 of the hearth. Slidably mounted in the rear of the chute 15 and so as to slide over the surface 4 of the hearth is a thrust bar 16. The bar 16 is perforated at its rear end to receive one arm 17 of a bell crank lever, the other arm 18, of which is connected by a link 19 with an arm 20 fixed to a treadle shaft 21 provided with a foot treadle 22. The arm 20 is held in raised position by a spring 23 which also maintains the bar 16 in its rearward position as shown in Figure 1. 90

When the articles are stacked in the chute 15 the lowest one rests upon the hearth just in front of the thrust bar 16. By pressing downwardly on the treadle 22, the arm 20 is rocked downwardly which, through the connection 19, rocks the bell crank 18, 17 so as to move the bar 16 forwardly. In this movement, as will be seen from Figure 6, the bar 16 moves the lower-most article out from under the stack and along the hearth. When 95 the treadle 22 is released the spring 23 will draw the parts back to their original position and the bar 16 will be driven out from beneath the stack, allowing the same to drop so as to place another article on the hearth and before the bar 16. As this operation is 100 repeated the articles are fed successively from the chute 15 and moved forwardly along the hearth.

The articles may be moved along the hearth 110 at such a rate that each becomes thoroughly heated by the time it reaches the forward or

discharge end of the hearth. The guide 5 terminates somewhat short of the end of the hearth and at this point the downward extension of the surface 4 provides a discharge 5 gate 24 from which the end-most article may slide off of the hearth when moved to this point by the successive crowding of the articles following. Suitably attached to the hearth at this point and arranged to receive 10 the articles discharged from the gate 24 is an inclined chute 25. In certain classes of articles such as those illustrated in the drawings which represent machine tool cutters, it is desirable to have the articles delivered in 15 oriented position, so that they may easily be taken from the delivery chute and transferred for subsequent operations. Such articles may have a body 26 and a laterally extending tip 27. Accordingly the chute 25 is provided with 20 a guide or cam 28 having a warped or twisted form adapted to be engaged by the tip 27 or other laterally extending part as the article slides down the chute and, by raising this tip, to turn the article in the chute to the oriented 25 position with the tip upstanding as illustrated in Figure 3. The chute may be provided with side notches 29 at its end adapted to expose a substantial portion of the article so that it may be gripped with tongs in order to remove 30 the same from the chute for subsequent operations.

In order to assist in guiding the articles in their movement along the hearth and to retain them in place on the hearth a movable guard 35 30 is hinged at 31 to the hearth. This guard extends over part of the surface 4 so that the other tip of the articles will move underneath the guard and be prevented from rising and becoming dislodged from the hearth. When 40 not required, the guard 30 may be turned on its hinge to inoperative position below the top of the hearth.

It will be seen, therefore, that this invention provides a convenient and economical 45 furnace for heating such articles as tool cutters and the like. The operator stacks a supply of articles in the chute 15 and feeds the same successively over the hearth. The flame of the burner 11 is directed on the hearth and 50 heats the articles in their passage thereover. By the time the first article has moved the length of the hearth, it has become thoroughly heated and is ready for delivery. The operator may then press the treadle 22 downwardly so as to operate the bar 16 to move another 55 article onto the hearth and at the same time force the foremost article into the gate 24 from which it slides downwardly into the chute 25. During such movement the guide 28 operates 60 to turn the article which is then delivered to the end of the chute 25 in oriented position to be taken out by the operator and transferred to such machine as is to perform a subsequent operation thereon. When the operation is in 65 full swing the articles will be moved across

the hearth at such a rate that each becomes thoroughly heated by the time it reaches the end of its travel. The air to be supplied to the burner 11 is first applied for cooling the hearth and is thereby itself heated so as to 70 be in better condition for combustion in the flame, thus a hot flame may be maintained so that a rapid heating of the cutters is obtained while at the same time the hearth is protected against over-heating. 75

It is obvious that various changes may be made in the details of construction without departing from the spirit of this invention; it is to be understood, therefore, that this invention is not to be limited to the specific details shown and described. 80

Having thus described the invention, what is claimed is:

1. A furnace for heating articles, comprising, a hearth, means for directing a flame on said hearth, means for moving the articles successively over said hearth, and a device at the end of said hearth positioned to receive the heated articles for movement endwise therealong, said device having means engaging the article to positively turn the same about its longitudinal axis during such endwise movement, in order to deliver the article in a definitely oriented position. 90

2. A furnace for heating articles, comprising, a hearth, means for directing a flame on said hearth, means for moving the articles successively over said hearth, and a delivery chute at the end of said hearth positioned to receive the heated articles for movement endwise therealong, the side of said chute being formed to engage the article along the side thereof in order to positively turn the same about its longitudinal axis during such endwise movement, in order to deliver the article 105 in a definitely oriented position. 100

3. A furnace for heating articles, comprising, a hearth having one side lower than the other and having a guide therealong, means for moving the articles over said hearth and along said guide, a guard along said hearth adapted to retain the articles thereon, and means for directing a flame on said hearth to heat the articles. 110

4. A furnace for heating articles, comprising, an inclined hearth having a guide therealong, means for moving the articles over said hearth and along said guide, a movable guard along said hearth adapted to retain the articles thereon, and means for directing a 115 flame on said hearth to heat the articles. 120

5. A furnace for heating articles, comprising, a hearth having one side lower than the other, and having a guide along the lower side thereof, means for moving the articles over said hearth and along said guide, a guard along said hearth adapted to retain the articles thereon, and means for directing a 125 flame on said hearth to heat the articles. 125

6. A furnace for heating articles, comprising, 130

ing a hearth having one side lower than the other, and having a guide therealong, means for moving the articles over said hearth and along said guide, a guard along the lower 5 side of said hearth adapted to retain the articles thereon, and means for directing a flame on said hearth to heat the articles.

7. A furnace for heating articles, comprising a hearth having one side thereof lower 10 than the other and having a guide therealong, means for moving the articles over said hearth and along said guide, a movable guard along the lower side of said hearth and above 15 said guide, adapted to retain the articles thereon, and means for directing the flame on said hearth to heat the articles.

8. A furnace for heating tool cutters and like articles, each having a body and a laterally extending lug, a chute adapted to receive and hold a stack of the articles, a hearth, 20 means for feeding the articles one at a time from the bottom of the stack to said hearth to be moved therealong by feeding succeeding articles, means for heating the articles on said 25 hearth, and means adapted to deliver the heated articles with their lugs in oriented position.

9. A furnace for heating tool cutters and like articles, each having a body and a laterally extending lug, an inclined chute adapted to receive and hold a stack of the articles, 30 an inclined hearth, means for feeding the articles one at a time from the bottom of the stack to said hearth to be moved therealong by feeding succeeding articles, means for heating the articles on said 35 hearth, and means adapted to deliver the heated articles with their lugs in oriented position.

10. A furnace for heating tool cutters and like articles, each having a body and a laterally extending lug, an inclined chute adapted to receive and hold a stack of the articles, 40 an inclined hearth, means for feeding the articles one at a time from the bottom of the stack to said hearth to be moved therealong by feeding succeeding articles, a guard along 45 said hearth covering the lower ends of the articles thereon, means for heating the articles on said hearth, and means adapted to deliver the heated articles with their lugs in 50 oriented position.

11. A furnace for heating tool cutters and like articles, each having a body and a laterally extending lug, a chute adapted to receive and hold a stack of the articles, a hearth, 55 means for feeding the articles one at a time from the bottom of the stack to said hearth to be moved therealong by feeding succeeding articles, means for heating the articles on said hearth, and means for delivering the 60 articles adapted to turn the same to oriented position.

12. A furnace for heating tool cutters and like articles, each having a body and a laterally extending lug, a chute adapted to receive 65 and hold a stack of the articles, a hearth, means for feeding the articles one at a time from the bottom of the stack to said hearth to be moved therealong by feeding succeeding articles, means for heating the articles on said 70 hearth, and means adapted to deliver the articles with their lugs up.

In testimony whereof I affix my signature this 23rd day of June, 1925.

JAMES B. MILLER.
